UNITED STATES PATENT OFFICE.

HORATIO L. PIERCE, OF PROVIDENCE, RHODE ISLAND.

SADDLE FOR THE TOP ROLLS OF SPINNING-MACHINES.

SPECIFICATION forming part of Letters Patent No. 298,621, dated May 13, 1884.

Application filed March 27, 1883. Renewed April 10, 1884. (No model.)

To all whom it may concern:

Be it known that I, HORATIO L. PIERCE, of Providence, in the county of Providence and State of Rhode Island, have invented certain new and useful Improvements in Saddles for the Top Rolls of Spinning-Machines; and I do hereby declare the following to be a full, clear, and exact description of the invention, such as will enable others skilled in the art to which it pertains to make and use it, reference being had to the accompanying drawings, which form part of this specification.

My invention relates to saddles for the top rolls of spinning-machines; and it consists in a saddle which is made of a single piece of metal that is bent so as to form a spring, and which has suitable bearing-pieces applied to its under side, all of which will be more fully described hereinafter.

The object of my invention is to produce a saddle which is made of a single piece, so as to be quickly and easily adjusted, and which will exert a greater pressure upon the front than the rear rolls, and which needs no lubrication.

In the accompanying drawings, Figure 1 is a side elevation of a saddle and top rolls embodying my invention. Fig. 2 is a perspective of the saddle alone.

A represents the top rolls, and B the lower rolls, and C the saddle. The saddle is formed of a single piece of elastic metal, bent, preferably, as shown, and which has a piece of rawhide or other suitable material, D, secured to one end, and a shorter piece, E, secured to the other. The piece, D, of rawhide is made long enough to rest upon two of the top rolls at once, while the shorter piece will rest upon a single roll alone. This saddle is placed upon the rolls so that the longer piece D will rest upon the two front rolls and the short piece upon the rear one. In the top of this saddle are formed a number of notches, in which the stirrup G catches, and which serve as guides in the adjustment of the stirrup. The stirrup has its upper end to catch over the top of the saddle in one of the notches, and has its lower end to extend downward any suitable distance, so that the weighted lever I can be passed through the slot in its lower end. Upon the outer end of the lever, which has its

fulcrum in the lower end of the stirrup, is placed a suitable weight, which may be adjusted back and forth, and thus regulate the pressure of the saddle upon the rolls.

I do not limit myself to the precise construction of the stirrup and the regulating-lever, as here shown, for they may be varied at will without departing from the spirit of my invention.

As a greater pressure is necessary for the front than the rear rolls, the direct weight of the weighted lever and the stirrup comes upon the stirrup near its front end, and thus exerts a much greater pressure at this point than upon the rear one. The front set of the rolls runs about five times as fast as the middle ones, and the greatest weight is consequently required on the top roll of this front set. The rolls that receive the sliver run the slowest, and require a less weight. The cotton comes into the machine between the rolls under the rear extension of the saddle farthest removed from the notches or slots.

This saddle, being made in a single piece, does away with all necessity of any parts to be adjusted so that they will bear the right relation to each other, and requires no further experience than to simply place the saddle in position. The saddles heretofore used have been made in two parts, and as they have to be often taken off to clean the roll, they are liable to be improperly adjusted when they are returned to position, and hence bad work results. Being made in two parts, and being in a difficult place to get at, they may be dropped, and the time of the operator is lost, and the machine may be idle when it should be at work. The saddle, being in the form of a spring, adapts itself to the roll, and maintains the proper degree of pressure on each, and conforms itself to the unevenness or inequality of the rolls, if they should be out of true, which often happens. The bend, curve, or arch in the spring stiffens it, and gives it the proper degree of pressure on the rear roll. This saddle may be applied to one, two, or more top rolls, and is not confined to spinning-frames proper, and is adapted to any drawing-rolls.

Rawhide or similar animal substance is used in connection with the saddle, and which rawhide, having oil in its substance, requires no

other lubrication. The use of oil is always damaging in connection with saddles. It is difficult to keep up that uniform supply and uniformity of action in the rolls that is indispensable to good work, and great damage to the work results when this uniformity is not maintained. The size of the roving is made to vary, making irregular work. The roving is broken, causing waste and the stoppage of the machine. The use of oil also results in discoloring the sliver, and when the oil gets in the rolls fibers adhere to the roll, causing waste and irregular pressure by widening the size of the roll, and necessitating the stoppage of the machine and the removal of the roll to clean it. Rawhide works uniformly without any oil or lubrication whatever beyond what it contains in itself. Lubricating oil also loosens and dissolves the cement by which the leather covering is secured to the frame, softens the leather, makes it stretchy, and causes it to wrinkle, and necessitates the re-covering of the roll.

Having thus described my invention, I claim—

1. A saddle for the top rolls of spinning-

machines, which is formed from a single piece of material, which is bent so as to form a spring, substantially as shown.

2. A saddle for the top rolls of spinning-
30 machines, formed from a single piece of elastic material, which is bent so as to form a spring, and which has a bearing piece attached to each of its ends, substantially as described.

3. A saddle formed from a single piece of metal, and bent so as to have its ends separated a suitable distance from each other, and a suitable bearing attached to each end, substantially as set forth.

4. In a saddle, the combination of a single piece of metal, which is bent, as shown, so as to form a spring, with pieces of rawhide, which are attached to the ends of the spring, substantially as specified.

In testimony whereof I affix my signature in presence of two witnesses.

HORATIO L. PIERCE.
